APPARATUS FOR APPLYING SHEET MATERIAL TO BOXES

Walter T. Bailey, Philadelphia, Pa., assignor to Stokes and Smith Company, Summerdale, Philadelphia, Pa., a corporation of Pennsylvania

Application January 18, 1940, Serial No. 314,375

31 Claims. (Cl. 93—40)

My invention relates to systems in which sheet material, such as wrappers, tabbed or untabbed, or tabs alone, is applied to box structures, stayed or unstayed, herein generically termed "boxes."

In accordance with one aspect of my invention, boxes are registered upon sheet material to form assemblies transported to a station at which walls or sides of each box, if unstayed, are erected, and from which station the assemblies are in turn transferred, with box walls held erect to a station at which the sheet material is further applied.

In accordance with another aspect of my invention, the transfer of boxes is effected by carriage structure movable above and clear of the box-supporting surface, for example that of a conveyor, and from which depends a group of box-holding members; preferably, the box-holding members embrace the front and rear corners of the box, and those members adapted to embrace the rear corners are lifted, during return of the carriage, to receive another box, so to permit positioning thereof for reception by the carriage before return movement of the carriage is completed.

Further in accordance with my invention, boxes, or aforesaid assemblies, are transported by a conveyor into engagement with a movable stop which returns each box or assembly into position of alignment with a form block to which transferred by said carriage; preferably, the stop, when so returning an unstayed box, coacts with another movable member to erect one pair of walls of the box.

Further in accordance with my invention, a pair of walls of an unstayed box is erected by coaction of another wall-erecting member with one pair of aforesaid box-holding members, specifically that pair which engages the leading corners of the box during transfer; preferably, a reciprocating member holds the box down against the conveyor or other supporting surface during operation of the wall-erecting member or members.

More particularly, all box-engaging members clear the conveyor to permit passage, beyond a stop, of sheet material which, through mischance, has not been assembled with a box; and, preferably, the sheet material, having so passed beyond the stop, is removed from the conveyor and disposed of, as by collection upon a roll adjacent the discharge end of the conveyor.

My invention further resides in the features of construction, combination, and arrangement, hereinafter described and claimed.

For an understanding of my invention, and for illustration of a preferred system and apparatus, reference is made to the accompanying drawings, in which:

- 5 Fig. 1 is a front elevational view, partly in section, and with parts broken away, of a complete machine embodying the invention;
- Fig. 1A, in perspective, shows significant elements of the machine disclosed in Fig. 1;
- 10 Fig. 2 is an end elevational view, on enlarged scale, of movable stop and wall-erecting members shown in Figs. 1 and 1A;
- Fig. 2A shows parts appearing in Fig. 2, as viewed from the left thereof;
- 15 Fig. 2B shows parts appearing in Fig. 2, as viewed from the right thereof;
- Fig. 3 illustrates parts appearing in Fig. 2 in another significant position;
- Fig. 3A shows parts appearing in Fig. 3, as viewed from the left thereof;
- 20 Fig. 4 is a plan view on enlarged scale of parts appearing in the prior figures;
- Figs. 5 and 6 are end and front views, respectively, partly in section, of carriage-driving mechanism, in part shown in Figs. 1 and 4;
- 25 Fig. 7, on enlarged scale and partly in section, shows carriage structure disclosed in Fig. 1;
- Fig. 7A is a detail view showing box-holding structure of Fig. 7, as viewed from the left thereof;
- 30 Fig. 8 is generally similar to Fig. 7, but shows the parts in another position;
- Fig. 8A is a detail view of a movable box-holding member of Fig. 8, as viewed from the left thereof;
- 35 Figs. 9 and 10 show parts disclosed in Figs. 7 and 8 in other significant positions;
- Fig. 9A, in perspective, shows details of the transfer carriage and driving mechanism therefor;
- 40 Fig. 10A is a detail view, in top plan and partly in section, of elements shown in Fig. 10;
- Fig. 11 is a view, on enlarged scale, of the discharge end of the conveyor and collecting roll shown in Fig. 2.
- 45 Referring to Figs. 1 and 1A, the mechanism BF, for transferring assemblies, each comprising an unstayed box B and a wrapper S, from conveyor C into the path of the form block F of a wrapping machine, comprises a pair of front carriers 1, 1, a pair of rear carriers 2, 2, a movable stop 3, blank-restraining plunger 25, an end palm 5 and a side palm 6. As the assemblies are moved by the conveyor C, each in turn engages stop 3 which, as hereinafter more fully explained,

moves the assembly in reverse direction into position of alignment with the form-block structure F.

Suitably after each assembly passes the end palm 5, the latter is moved downwardly to the left, as viewed in Fig. 1A, to engage the rear wall RB of the box structure and coacts with the stop 3, in engagement with the front wall FB of the box structure, to bring both the front and rear walls FB, RB into their erect or box-forming positions.

Substantially upon completion of this erection of the end walls of the box blank B, the front carriers 1, 1 move from the position shown in Fig. 1A toward the position shown in Fig. 1, and substantially concurrently with this movement of the front carriers, the side palm 6 descends and moves toward them to effect erection of the side walls BL and BR of the box-blank B. Thereupon the rear carriers 2, 2 descend and move towards the front carriers to embrace the two corners of the box at the ends of the now erected side wall BL. Thus the four walls of the unstayed box are brought to box-simulating position and held therein by the four carriers which remain in fixed relation with respect to each other as they all move together as a unit to transfer the assembly across the conveyor C into the path of the form block F of the wrapping machine W.

The wrapping machine disclosed is of the two-stage or double-plunger type disclosed and claimed in U. S. Bailey Patent #2,119,980; it is to be understood, however, that the mechanism BF for erecting and feeding unstayed boxes may be utilized with other types of wrapping machines, for example, those of the single-plunger or single-stage type exemplified by U. S. Federwitz Patent #2,044,606.

The movements of the various components of the mechanism BF, are derived from the shaft 7, Fig. 1, which makes one revolution for each cycle of the wrapping machine W; the connection between shaft 7 and the drive for the wrapping machine W is hereinafter described.

For description of the mechanism which operates the plunger 4 and the stop 3, reference is made to Figs. 1, 2, 2A, 3, 3A, 4, 7, 9 and 10.

Referring to Figs. 1, 4 and 5, the bevel gear 8 at the upper end of shaft 7 meshes with a similar gear 9 attached to shaft 10 which drives the cam shaft 11 through the gears 12, 13 and 14. The groove in the face of cam 15, one of three cams attached to shaft 11, receives the cam follower or cam roller 16 attached to the lever 17 which is pivotally mounted on shaft 18. The arm 17 is connected by link 17A to arm 19 secured to the shaft 20 which passes through the adjustable frames 21 and 22 which, as hereinafter described, support the rear and front carriers, the stop 3, and the end palm 5.

To the shaft 20 intermediate the frames 21, 22, is attached the arm 23 connected by link 24 to the blank-restraining plunger 25. As appears most clearly in Fig. 9, the plunger is received by the guide 26 supported by bars 27 and 28 which also support the adjustable frames 21, 22; the ends of the bars 27, 28 pass through and are attached to the stationary frame members 29, 30 of the wrapping machine W Fig. 4.

The movements of the plunger 25 are so timed by the cam 15 that it moves down to engage the bottom panel of a box blank B after the leading panel FB of the blank has passed beyond the path of reciprocation of the plunger; it remains down

during the wall-erecting operations of the palms 5 and 6 to avoid any tendency for the box blank to raise from the surface of the conveyor when engaged by these wall-erecting members. Preferably, as shown, the plunger 25 does not engage the box directly but carries a heavy metal roller 31 whose axle 32 is received by vertical slots 33 in the bifurcated end of the plunger 25. When the plunger is in its "down" position, the weight of the roller 31 is entirely carried by the blank; the roller, however, permits the blank B to move in contact with the conveyor during the aforesaid aligning and wall-erecting operations.

Referring particularly to Figs. 2, 2A, 2B, 3 and 4 for illustration of the operating mechanism for movable stop 3, the end of shaft 20 which extends through and beyond the frame 22 is slidably keyed, or similarly attached to the hub of arm 34 connected by link 35 to the upper end of arm 36 whose shaft 37, supported from the frame member 22, is attached to bevel gear sector 38. To the shaft 39, supported by bracket 40 from the frame member 22, is attached a bevel gear 41 in mesh with aforesaid bevel gear 38. The forked arm 42 is attached at its upper end to the shaft 39 and between its lower forked end is pivotally mounted the arm 43 to whose lower end, as viewed in Figs. 2 and 2A, is attached the stop member 3.

The arm 43, as most clearly appears in Fig. 2, is mounted on pin 44 extending between the forked end of the arm 42, and is also pivotally connected at 45 to the arm 46 supported at its upper end upon the stationary pin 47 extending from the bracket member 40.

As shaft 20 is oscillated, the stop 3 moves toward and from the positions shown in Figs. 2 and 3. The timing of the movements of stop 3 by cam 15 is such that, as above explained, it is engaged by the box structure while moving with conveyor C beyond the position from which it is transferred to the form block; by downward and angular movement of stop 3 in counterclockwise direction, as viewed in Fig. 2, each box blank is moved in reverse direction to position of exact alignment of its end walls with the ends of the form block. Use of a fixed stop for alignment of the box structures is avoided because of tendency of the box structure to rebound therefrom to indefinite position; by use of the movable stop 3, even if there is rebounding, the stop 3 reengages the box structure and moves it to the desired position.

Whether or not a box in moving with conveyor C fails to reach stop 3, the end palm 5 and stop 3 cooperate to erect the end walls of the box, if unstayed, and to align it with the form block.

Preferably the stop 3 is always somewhat above the surface of the conveyor so that in event there has been failure of registration of a box blank upon a wrapper being transported by the conveyor, the wrapper will pass below the stop. These unused or waste wrappers are preferably disposed of by causing them to wind about the roller 48 at the discharge end of the conveyor C, Figs. 2 and 11. More particularly, the roller 48 is supported by engagement of the ends of its shaft with the pivotally mounted supporting members 50, 50 at the discharge end of conveyor C. The periphery of the roller 48 is preferably grooved for retention of the edges of a sheet of paper wrapped about the roll to prevent engagement of the coated surface of a wrapper with the face of the roll. As an unused wrapper passes off the end of conveyor C, its coated surface engages the paper-covered surface of the roller 48 which,

driven by engagement with the belt C, rolls or draws the wrapper about it. Roller 48 is biased toward the end of conveyor C by spring 49 coiled about rod 49A connected to one arm of bell crank lever 50 and slidable through the pivotally mounted block 49B. From time to time the roller 48 may be removed from the machine for disposition of the unused wrappers which have accumulated upon it.

Referring to Figs. 1A, 2, 2B and 4 for illustration of the mechanism for operating the palms 5 and 6, the cam 51, on shaft 11, (Fig. 4) is provided with a groove in one face thereof to receive the cam roller 52, carried by the arm 53, pivotally mounted on pin 18. The free end of the arm 53 is connected by link 54 to arm 55 of a bell-crank lever whose other arm 56 is connected by rod 57 to the arm 58 attached to shaft 59 which passes through the frame member 29 of the wrapping machine, frame member 21 of the box-transfer mechanism DB, and, as appears most clearly in Fig. 9, the plunger-supporting member 26.

To the shaft 59, as most clearly appears in Figs. 4 and 9, there is attached arm 60 connected by slotted link 61 to the upper end of lever 62 supported upon the pin 63 which extends from a block 64 adjustable along the bar 65 extending from the plunger support 26. The support 66 (Fig. 9) for the palm member 6 is pivotally mounted intermediate its ends upon the pin 67 supported at the lower end of the arm 62 and is pivotally connected at one end by pin 68 to the arm 69 pivoted at its upper end 70 upon the aforesaid adjustable block 64.

To adjust the side palm 6 to suit different widths of boxes, the set screw 71 is loosened to allow the block 64 to be moved along the guide bar 65 to proper position; it is also necessary to loosen the clamping screw 72 for corresponding adjustment of the pivotal connection between the upper end of arm 62 and the slotted link 61.

The palm 6 is so timed by the cam 51 that, as above explained, it moves downwardly and angularly in counterclockwise direction, as viewed in Fig. 9, to erect the side wall BL of a box blank which has been transported by conveyor C into position for transfer by the carriers 1, 1, and 2, 2.

The mechanism for effecting operation of the end palm 5 is most clearly shown in Figs. 2, 2B and 3. The gear segment 73, slidably keyed to shaft 59 for movement with the frame 21, is continuously in mesh with the rack 74 of the vertically reciprocable member 75 whose upper end is guided by the projection 76 of the frame 21 and whose lower end is guided by the bracket 77 attached to and extending from the frame 21; the lower end of the member 75 is provided with a rack 78 in mesh with the gear sector 79 attached to the shaft 80 supported by the bracket 77. The support 81 for the palm 5 is pivotally mounted intermediate its ends upon the pin 82 carried by the arm 83 attached to shaft 80 and is pivotally connected at 84 to one end of arm 85 whose other end is pivoted upon pin 86 extending from bracket 77.

Accordingly, as the shaft 59 is oscillated, the palm member 5 moves to and fro between the position shown in Fig. 2, at which it is clear of the path of boxes moving toward the transfer station, and the position shown in Fig. 3. In moving from the position of Fig. 2 to that of Fig. 3, the palm member 5, as previously de-

scribed, engages the end wall RB of an unstayed box and moves it to its erected or box-forming position. The palm 5 and stop 3 are returned to their positions of Fig. 2 in time to avoid obstruction to the rear carriers 2, 2 during their movement towards the form block of the wrapping machine.

Each of the frames 21, 22 supports a reciprocating carriage upon each of which is mounted one of the front carriers and the corresponding rear carrier; since those two carriages are practically identical in construction, only one of them need be specifically described.

Referring particularly to Figs. 7, 7A, 8, 8A, 9, 9A and 10, the pair of flat strips or bars 87, 87 attached to frame 21 are spaced to provide a trackway for the grooved carriage member 88 to which is adjustably clamped the front carrier 1. As more clearly shown in Fig. 7A, the clamping bolt 89 passes through the front carrier 1, the spacer 90, the slot 91A of carriage member 88, and threads into the clamping plate 91 of the other side of the web of member 88.

The block 92 for supporting the rear carrier 2 is similarly adjustably clamped to the carriage member 88, Fig. 10A. The holder or carrier 2 is pivotally mounted upon one end of arm 93 whose other end is pivoted on pin 128 extending through plates 92. The arm 93 is adapted to be swung about pivot pin 128 to raise and lower the carrier 2 by mechanism hereinafter described. The supporting member 95 for the carrier 2 is pivotally connected to the plates 92 by the link 96.

The reciprocation of carriage member 88 is derived from a chain 99 which passes over the idler sprocket 100 and driven sprocket 101 both supported within frame 22; a generally similar sprocket arrangement is carried by the frame 21 for actuation of the other carriage member 88.

As shown in Fig. 5, the sprocket 101 associated with frame 21 is keyed to a stub shaft 102 extending through the frame and to which is attached a gear 103 driven by gear 104 slidably keyed to shaft 105 and attached to bushing 106 rotatable within frame 21. The shaft extends through the stationary frame member 29 of the wrapping machine for attachment thereto of gear 107 driven by gear 108 on shaft 10. As more clearly appears in Fig. 6, the gears 107 and 108 are mutilated gears providing for intermittent drive of shaft 105 and, therefore, of the chains 99, for continuous rotation of shaft 10.

Sprocket 101 associated with frame 22 is similarly mounted and is similarly driven from the shaft 105 by another pair of gears 103, 104 both adjustable with frame 22 as it is moved toward and away from the dotted center line Z-Z which passes at right angles to conveyor C through the line of travel of form-block F.

Each of the chains 99 is connected to its associated carriage member 88 by a link 109, Fig. 9A. As the sprockets rotate, the carriage members 88 are moved in unison between their box-receiving position, Fig. 7, and their box-delivering position, Fig. 8.

A dwell of the carriage members at their box-receiving position above the conveyor C is provided by the intermittent gears 107, 108; dwell of the carriage members at their box-delivering position, Fig. 8, is provided, without interruption of movement of chains 99, by the construction of the links 109, 109.

Each of the links, Fig. 9A, essentially consists of two members having a resilient connection be-

tween them. Specifically, the link member 110 pivotally attached to carriage member 88 slidably receives the link member 111 pivotally attached to the chain 99. The spring 112, between the block 113, attached to link member 111 and slideable within the slot 114 of link member 110, and an end of the slot 114, provides for a yielding connection between the two link members 110, 111.

When the carriage members 88 arrive at their box-delivering position, Fig. 8, each of them is arrested by a stop member 115 attached to the guide bars 87. The carriage members 88 arrive at this position when the pivot pin of link member 111 reaches the position X, Fig. 8. Further movement of the chains simply compresses the springs 112 of the links 109 and effects no further movement of carriage members 88 until the pivot pin of link members 111 pass beyond the position Y, Fig. 8, whereupon the carriage members for continued movement of chains 99 begin their return movement towards the position shown in Fig. 7.

The dwell afforded by the extensible links 109, 109 affords sufficient time for the form block F of the wrapping machine to enter the box structure held by the box-holders 1, 1 and 2, 2 and to move with it beyond the path of return movement of the front box-holders 1, 1.

During the transfer, into the path of form block K, of each assembly comprising a box structure B and partially applied wrapper S, the leading unapplied panel LS of the wrapper is supported as it moves beyond the side of the conveyor and over the platen P of the wrapping machine by two pairs of grippers, each pair of which is movable with one of the carriages 88, 88.

Referring to Figs. 7, 7A, 8, 9, 9A and 10, the gripper-supporting member 116 is slidably received by the extension 117 of the carriage member 88. Upon the lower end of member 116 is pivotally mounted the movable gripper member 116A, biased by spring 118 toward engagement with the gripper roll 119 rotatably mounted on a pin extending from member 116.

The spring 121 compressed between the block 122, attached to the carriage extension member 117, and the gripper supporting member 116 biases the latter towards the left, as viewed in Fig. 8, to effect engagement between the adjustable stop 123 of gripper slide 116 and the box holder 1.

As carriage member 88 moves to the left toward the position shown in Fig. 7, the pin 124, fixedly attached to the gripper slide 116, is arrested by stop 125 attached to the frame member 22 so that for further movement of carriage member 88 to the left, to the position shown in Fig. 7, the gripper-supporting member 116 is restrained in the position shown in Fig. 7 with spring 121 compressed. As the gripper slide 116 moves with carriage 88 approaches the position shown in Fig. 7, the lower gripper member 116A engages a stop, which conveniently may be the edge of the suction housing for conveyor C, and is rocked away from the upper gripper member 119 upon continued movement of member 116 in counterclockwise direction about its pivot pin.

As the carriage members 88 move to the right, with their box holder 1, 1, and 2, 2 carrying between them a box and wrapper assembly, the edge of the leading unapplied panel LS of the wrapper S passes between the separated gripper elements 116A, 119; as movement of the carriage continues, the gripper supports 116 are moved to

the right, Fig. 7, away from engagement with the suction housing, whereupon the biasing springs 118 swing the movable grippers 116A to clamp the leading panel LS and prevent it from curling or otherwise moving into engagement with the platen P, or any other part of the wrapping machine, during transfer of the box and wrapper assembly to the delivered position shown in Fig. 8. As form block F descends, to move the assembly downwardly from the position shown in Fig. 8, the edge of the panel LS is withdrawn from the gripper rolls. When the carriage members 88 return for the next assembly, the grippers are opened, as above described, to receive the leading panel of the wrapper of that assembly.

Movement of each of the rear box holders 2 from the raised position of Figs. 9 and 10 to the lowered position of Figs. 7 and 8, is effected by mechanism including channel bar 126 which receives a roller 127 (Fig. 10A) carried by supporting arm 93 of the gripper; the slot or groove in bar 126 serves as a guide or trackway for roller 127. Accordingly when bar 126 is in the upper position shown in Figs. 9 and 10, the arm 93 is retained thereby in its upper position to hold the rear box holder 2 in raised position; when the bar 126 is in its lower position, the arm 93 is retained in its lower position, Figs. 7 and 8.

Bar 126 is supported at its opposite ends by pivotal connection at 129 and 130 to the arms 131, 132 of the bell-crank levers 134, 135 pivotally mounted at opposite ends of the frame 22. It is understood, of course, that with frame 21 there is associated a corresponding pair of bell-crank levers identified by similar reference characters for supporting another bar 126 operable to raise and lower the rear box holder 2 associated with the carriage 88 reciprocable along frame 21. Each pair of bell-crank levers 134, 135 is connected by a link 136 for effecting their operation in unison to raise and lower one of the guide bars 126 while maintaining the bar substantially parallel to the path of travel of the associated carriage member 88.

The bell-crank levers 134, 134 at the forward ends of the frames 21 and 22 are slidably keyed to the shaft 137 supported at its opposite ends, Fig. 4, by the frame members 29 and 30 of the wrapping machine. The lever 138 attached to one end of shaft 137, Figs. 1 and 4, is connected by link 139 to one arm of a bell-crank lever 140 loosely mounted on shaft 20 and whose other arm is connected by a link to arm 141 pivotally mounted on pin 18, Fig. 4, and carrying a cam follower 142 received by a cam slot or groove in the face of the cam 143 attached to shaft 11.

The cam 143 is constructed to lift the guide bars 126 before return movement of the box holders 2 from the position shown in Fig. 8 over the conveyor surface C, thus to permit feed of the next assembly by conveyor C to the transfer station during the return stroke of the box transfer carriage; the rear box holders 2 remain in their upper position until after the side walls of the box have been erected by cooperation of palm 6 with the front box holders 1. Then, under control of cam 143, the bars 126 are lowered; substantially concurrently, the carriages 88 under the control of the intermittent gears 107, 108, Fig. 6, move forward so that the two rear box holders 2 move downwardly to engage the rear corners of the box structure and forwardly to push the box structure from the position shown in Fig. 10 to the position shown in Fig. 7. The box structure, whether it be a stayed box or

an unstayed box, is therefore firmly held by the four box holders in precise alignment with the form block to which it is transferred as above described by further forward movement of the carriages 88.

After an assembly, comprising a box structure and partially applied wrapper, has been received by the form block of the wrapping machine, the additional sheet-applying operations may be effected in any desired manner or by any desired mechanism. In the particular double-plunger machine shown, the downward movement of the form block F from the position shown in Fig. 8 is effective to clamp the assembly against the platen P. As downward movement of the form block continues, the side panels of the wrapper are applied to the side walls of the box structure by the rolls 144, Fig. 1, and are wiped into more intimate engagement therewith by the brushes 145, 145. As the form block F approaches the lower limit of its stroke, it positions the partially wrapped box within the box holders of a reciprocating carriage 146 which, after the ascending form block F clears the box, moves to the right, Fig. 1, to position the partially wrapped box in the path of movement of a second form block F' and to move out of the machine a completely wrapped box stripped from the form block F' in its prior cycle of operation.

As the form block F' descends from the position shown in Fig. 1, supplemental sheet-applying operations are performed upon the box and wrapper assembly by the rolls 147, which apply the end panels of the wrapper to the end walls of the box, by the marginal turn-in tools 148, and by the pressing tools 149. As the form block F' ascends to the position shown in Fig. 1, the strippers 150 remove the completely wrapped box which is ejected from the machine by the carriage 146 as it transfers the next assembly to be completed.

The reciprocation of the form blocks F and F', the operation of the various sheet-applying tools disposed along their paths of movement, and the reciprocation of the transfer carriage 146, are all derived from the barrel cams 152, 153 driven from a suitable source of power, not shown, through the one-cycle clutch mechanism 154; the barrel cams 152, 153 are connected by suitable gearing to make one revolution for each cycle of the machine. The gearing between shaft 7, from which all movements of the transfer mechanism BF is derived, and the bevel gear 155 secured to the barrel cam 152 is such that shaft 7 makes one revolution for each cycle of the machine. This gearing, as shown in Fig. 5, may include the bevel gears 156, 157, attached to shaft 158 supported by the frame of the machine, respectively engaging the gear 155 and gear 160 attached to shaft 7.

For a more complete description of the construction and operation of the two-plunger wrapping machine W, reference is made to aforesaid Bailey Patent #2,119,980.

To adjust the box transfer mechanism BF to suit boxes of different length, the frames 21, 22 are moved toward or away from the center line Z—Z, Fig. 4. In the preferred arrangement shown, the frames are adjusted individually toward or away from each other by rotation of the cranks 161 secured to shafts 162 which pass through the frame members 29, 30 of the wrapping machine and threadably engage the side frames 21 and 22, respectively. To suit the mechanism BF for boxes of different width, the

supporting block 64 for the side palm 6 is adjusted, as previously described, along the bar 65; and the pivotal connection of the supporting arm 62 for the palm 6 to the link 61 is correspondingly adjusted, also as above described; the position of the front box holders 1, with respect to their respective carriages, is modified by loosening the clamping bolts 89, setting the holders to their proper position, and then retightening the bolts 89, all as previously described.

The rear holders 2 are adjusted by loosening the clamping bolts 163, Fig. 10A, and sliding the supporting plates 92 to proper position; bolts 163 are then retightened.

To adjust the grippers 116 to suit boxes of various depths, the stops 123 are adjusted to obtain the desired spacing between box holders 1, Fig. 8, and the grippers.

What I claim is:

1. A system for applying sheet material to unstayed boxes comprising a movable form block, sheet-applying mechanism associated therewith, a conveyor for transporting unstayed boxes, mechanism for erecting walls of an unstayed box on said conveyor, and means, for transferring each of the unstayed boxes in turn from said conveyor into the path of said form block, including members embracing the corners formed by aforesaid erection of box walls and cooperating to hold the walls erect during the transfer.

2. A system for applying sheet material to unstayed boxes comprising a movable form block, sheet-applying mechanism associated therewith, a conveyor for transporting unstayed boxes, mechanism for erecting adjoining walls of an unstayed box on said conveyor, structure movable toward said conveyor to hold a box against it during erection of its aforesaid walls by said mechanism, and means operable after movement of said structure away from said conveyor to transfer the box, with its aforesaid walls erect, from said conveyor into the path of said form block.

3. A system for applying sheet material to unstayed boxes comprising a movable form block, sheet-applying mechanism associated therewith, structure movable toward and away from the path of said form block, members extending from said structure to embrace the corners of a box, and mechanism for erecting the adjoining walls of an unstayed box to be transported by said structure with its aforesaid corners, formed by the erected walls, embraced by said members.

4. A system for applying sheet material to unstayed boxes comprising a movable form block, sheet-applying mechanism associated therewith, a conveyor for transporting said boxes, structure movable above said conveyor toward and away from the path of said form block, mechanism for erecting all walls of an unstayed box on said conveyor below the path of said structure, and members depending from said structure jointly to surround and hold the box with its walls erect during transfer of the box by said structure into the path of said form block.

5. A system for transporting boxes into the path of a form block comprising a conveyor for boxes, stop structure engaging a box on the conveyor beyond position of alignment with the form block, mechanism for moving said stop structure to predetermined extent to return the box to said position of alignment, and structure movable transversely of the conveyor for

engaging the aligned box and moving it into said path.

6. A system for transporting unstayed boxes into the path of a form block comprising a conveyor for the boxes, movable stop structure for engaging a box on the conveyor beyond position of alignment with the form block, a wall-erecting member, mechanism for moving said stop structure to return the box to said position of alignment and concurrently moving said member toward said stop structure to effect erection of opposite walls of the box, and structure movable transversely of the conveyor for engaging the aligned box and moving it, with its walls erect, into said path.

7. A system for applying sheet material to unstayed boxes comprising a movable form block, sheet-applying mechanism associated therewith, members movable toward each other to erect a pair of opposite walls of an unstayed box, structure movable toward and away from said form block, a pair of box-engaging members extending from said structure, a member movable toward said box-engaging members and coacting therewith to erect another pair of opposite walls of the box, and another pair of box-engaging members extending from said structure and coacting with said first-named pair of box-engaging members to hold the box with its walls erect during movement of said pairs of box-engaging members with said structure toward the form block.

8. A system for transporting unstayed boxes into the path of a form block comprising a conveyor for unstayed boxes, movable stop structure for engaging an unstayed box on the conveyor beyond position of alignment with the form block, mechanism for moving said stop to predetermined extent to return the box to said position of alignment, mechanism for erecting the walls of the aligned box, and structure movable above the conveyor for transporting the aligned box, with all of its walls held erect, into said path.

9. A system for applying sheet material to box structures comprising a movable form block, sheet-applying mechanism associated therewith, and means for transferring assemblies, each comprising a box structure and sheet material partially applied thereto, to said form block including carriage structure movable toward and away from said form block and having depending therefrom clamping members movable relatively to each other to embrace box corners formed by erect walls of said box structure.

10. Mechanism for transferring boxes from a conveyor into the path of a form block comprising carriage structure reciprocable above and transversely of said conveyor, box-clamping members depending from said carriage structure adapted to embrace a box on said conveyor, and mechanism controlling relative movement of said members to effect their clamping engagement with a box to be transferred from the conveyor and to prevent engagement with the box next to be transferred by any of said members during their return with said carriage structure.

11. Mechanism for transferring boxes from a conveyor into the path of a form block comprising carriage structure reciprocable above and transversely of said conveyor, a set of members depending from said carriage structure adapted to embrace the forward corners of a

box on said conveyor, another set of members depending from said structure adapted to embrace the rear corners of said box, and mechanism effecting movement of the members of one of said sets toward said conveyor and toward the members of the other set to clamp upon the box to be transferred from the conveyor, retaining said members in clamping position until after said form block has removed the transferred box from therebetween, and effecting reverse movement of the members of said one of said sets for return of said carriage structure to avoid obstruction by or to the box next to be transferred thereby.

15. 12. A system comprising sheet-applying mechanism, a conveyor for transporting adjacent said mechanism assemblies each comprising a box structure and sheet material partially applied thereto, and means for transferring the assemblies in turn from said conveyor to said sheet-applying mechanism comprising carriage structure movable transversely of said conveyor, and clamping elements on said carriage structure relatively movable to embrace box corners formed by the erect walls of one of said box structures.

20. 13. A system for applying sheet material to unstayed boxes comprising a conveyor for transporting the boxes, a machine adapted to apply sheet material to the boxes, a frame extending from said machine above said conveyor, mechanism supported by said frame including members movable to engage and erect all walls of each unstayed box upon the conveyor as it in turn arrives below said frame, and a carriage reciprocable on said frame for in turn transferring the unstayed boxes, with their walls erect, from said conveyor to said machine.

25. 14. A system comprising sheet-applying mechanism, a conveyor for transporting assemblies each comprising box structure attached to sheet material, mechanism for transferring the assemblies from said conveyor to said first-named mechanism and all of whose components are disposed above said conveyor to permit unobstructed movement with said conveyor of waste sheet material, and means adjacent said conveyor and beyond said transfer mechanism for directing said waste sheet material from said conveyor and collecting it.

30. 15. An endless conveyor for transporting sheets freshly coated with adhesive toward and beyond an assembly station and for transporting assemblies including said sheets from said station to a transfer station, and a roll at the discharge end of said conveyor for accumulating waste sheets not assembled at said assembly station and transported by the conveyor beyond said transfer station.

35. 16. In a system for transferring an unstayed box from a station into the path of a form block, mechanism for erecting walls of a box at said station, and mechanism for transporting the box into said path including members relatively movable to erect other walls of said box.

40. 17. A system for transferring an assembly, comprising an unstayed box and sheet material partially applied thereto, from a station into the path of a form block, comprising mechanism at said station for erecting walls of said box, and means for transferring the assembly comprising reciprocating structure, members extending therefrom to embrace the corners of the box to hold said walls erect during transfer, and means

carried by said structure for gripping the leading unapplied edge of the sheet material to hold it during transfer in predetermined position with respect to the box.

18. A system for transferring from a conveyor an assembly, comprising a box disposed upon sheet material partially applied thereto, which comprises a transfer carriage movable above and away from said conveyor, box-engaging means on said carriage, and sheet-gripping structure movably mounted upon said carriage for receiving the leading edge of the unapplied sheet material when moved beyond said conveyor with said carriage and for gripping said edge upon movement of said structure with said carriage during further movement thereof away from said conveyor.

19. A system, for transferring an assembly comprising a box disposed upon sheet material partially applied thereto from a conveyor, including a transfer carriage movable above and away from said conveyor, box-engaging members depending from said carriage, a sheet-gripping device slidably mounted upon said carriage, means for biasing said device toward said members and to gripping condition, and stop structure for arresting said device and opening it to receive sheet material upon movement of said carriage toward and over said conveyor, said biasing means, upon reverse movement of said carriage to transfer an assembly from the conveyor, operating said device to grip the leading unapplied edge of the sheet material and maintain it in predetermined position with respect to its box during the transfer.

20. Mechanism for transferring boxes from a receiving station to a discharge station comprising carriage structure movable above said stations, box-clamping members depending from said structure, and mechanism for effecting relative movement of said members in one direction to effect their clamping engagement with the corners of a box to be transferred from said receiving station and for effecting reverse relative movement thereof for return of said structure to said receiving station without obstruction by or to the box next to be transferred.

21. Mechanism for transferring boxes from a receiving station to a discharge station comprising structure movable above said stations, members depending from said structure to embrace leading corners of a box, members movably attached to said structure for embracing trailing corners of the box, and mechanism for lowering said movable members while said structure is above said receiving station to cooperate with said first-named members in holding a box for transfer from said receiving station and for lifting said movable members for return of said structure from said discharge station to said receiving station without obstruction by or to the box next to be transferred.

22. In a system for transferring an unstayed box from a station, mechanism comprising members relatively movable to erect walls of said box at said station; structure for engaging the bottom of said box to prevent its displacement during operation of said wall-erecting mechanism, and means for transferring the box from said station including members embracing corners thereof formed by its erected walls.

23. In a system for transferring an unstayed box from a station, carriage structure movable toward and from said station comprising a pair of members for embracing leading corners of a box and a second pair of members for embracing

trailing corners of the box, structure movable toward the members of one of said pairs to erect opposite walls of the box, structures movable toward each other between said pairs of members to erect other walls of the box, and mechanism controlling relative movement of the members of said pairs firmly to hold the box with its walls erect during its transfer by said carriage.

24. Mechanism for transferring boxes from a station comprising a pair of slides reciprocable above said station and each having a pair of relatively movable box-engaging members depending therefrom, mechanism effecting reciprocation of said slides in unison with each other, and mechanism controlling said pairs of members to effect their clamping upon a box at said station for transport therefrom by movement of said slides.

25. Mechanism for transferring boxes from a station comprising a slide reciprocable above said station, a box-engaging member pivotally suspended on said slide, structure extending adjacent the path of movement of said slide and movable to determine the angular position of said member with respect to said slide, and means for actuating said structure in timed relation to reciprocation of said slide to effect engagement of said member with a box at said station prior to movement of the slide therefrom and to position said member to clear a box at said station during return of the slide thereto.

26. In apparatus of the character described, a carriage, and means effecting intermittent reciprocation thereof with a dwell at each end of each stroke thereof comprising an endless belt-like member, mechanism imparting to said member unidirectional movement with interruption thereof to provide the dwell of said carriage at one end of its stroke, and means providing the other dwell of said carriage at the other end of its stroke during movement of said member comprising an extensible link connecting said carriage to said member, and stop structure preventing movement of said carriage and causing extension of said link for the extent of movement of said member occurring during said last-named dwell.

27. In apparatus of the character described, structure providing a supporting surface for a box, a pair of frames adjustable toward and from each other above said surface to accommodate boxes of different sizes, slides reciprocable on said frames, and complementary box-holding members carried by and depending from said slides respectively and terminating short of said surface.

28. In apparatus of the character described, structure providing a supporting surface for an unstayed box, a pair of frames adjustable toward and away from each other above said surface, complementary wall-erecting members carried by and depending from said frames, and mechanism carried by said frames for operating said members to erect walls of said box.

29. In apparatus of the character described, structure providing a supporting surface for an unstayed box, a member movable toward and from said surface to hold said box thereto, a pair of frames disposed on opposite sides of said member, above said surface and adjustable toward and away from each other, complementary wall-erecting members carried by and depending from said frames, and mechanism carried by said frames for operating said last-named members, while said first-named member is holding a box, to effect erection of walls of the box.

30. In apparatus of the character described, a pair of frames extending on opposite sides of and adjustable toward and from a form block, a carriage for transferring box structures into the path of said form block comprising reciprocable members each carried and guided by one of said frames, mechanism adjustable with said frames comprising members each carried by one of said frames and coupled to each other, and means for driving said members in unison.

31. A system comprising a conveyor for trans-

porting to a transfer station assemblies each comprising an unstayed box structure and sheet material partially applied thereto, structure movable toward said conveyor to press against it an assembly at said station, and members movable toward each other in timed relation to movement of said structure to erect walls of each unstayed box structure while pressed against said conveyor.

10

WALTER T. BAILEY.
